[57] ABSTRACT

Embodiment No. 1. Urea phosphate prepared from wet-process phosphoric acid is heated with monopotassium orthophosphate in a mole ratio of 0.25 to 4.0 at 130° to 200° C. to form an ammonium potassium polyphosphate having an average chain length between 1.2

and 2.5. The ammonium potassium polyphosphate is dissolved in aqueous ammonia to yield concentrated fertilizer solutions containing the three major nutrients and over 50 percent total plant food.

Embodiment No. 2. Phosphoric acid containing 54 to 76 percent P₂O₅ is heated with urea (urea:H₃PO₄ mole ratio 0.5 to 2.0) and monopotassium orthophosphate (urea:KH₂PO₄ mole ratio 0.25 to 4.0) at 130° to 200° C. to form an ammonium potassium polyphosphate having an average chain length between 1.2 and 2.5. The ammonium potassium polyphosphate is dissolved in aqueous ammonia to yield concentrated fertilizer solutions containing the three major nutrients and over 50 percent total plant food.
